Des. 185,829
Patented Aug. 4, 1959

185,829

LADY'S POUCH

Le Roy Paul Lemler, West Bend, Wis., assignor to Amity Leather Products Co., West Bend, Wis., a corporation of Wisconsin

Application April 24, 1958, Serial No. 50,603

Term of patent 14 years

(Cl. D87—3)

FIG. 1

FIG. 2

Fig. 1 is a top plan view of a lady's pouch showing my new design; and

Fig. 2 is a front elevational view.

The dominant features of my design are shown in full lines on the drawing.

I claim:

The ornamental design for a lady's pouch, substantially as shown and described.
